FIG. 1

FIG. 2

FIG. 3

FIG. 4

FIG. 1 is a front elevation of a portion of a grille embodying my new design, a rear elevation thereof being the same in appearance but interposed in alternating relation with the front;

FIG. 2 is a vertical section, taken along line 2—2 of FIG. 1;

FIG. 3 is a fragmentary horizontal section, taken along line 3—3 of FIG. 1; and

FIG. 4 is a front elevation of a portion of a grille also embodying my new design and similar to the design of FIG. 1 but treated to provide a weathered appearance, a rear elevation thereof being the same in appearance.

This application is a division of my copending application Ser. No. D. 14,032, filed Oct. 17, 1968, now Pat. No. D. 216,463.

I claim:

The ornamental design for a grille, as shown and described.
